UNITED STATES PATENT OFFICE

HOWARD H. SCHOTT, OF ROCHESTER, NEW YORK, ASSIGNOR TO ROBESON-ROCHESTER CORPORATION, OF ROCHESTER, NEW YORK, A CORPORATION OF NEW YORK

DESIGN FOR A COMBINED CASSEROLE AND TRAY

Application filed September 18, 1930. Serial No. 37,013. Term of patent 3½ years.

To all whom it may concern:

Be it known that I, HOWARD H. SCHOTT, a citizen of the United States, residing at Rochester, in the county of Monroe and State of New York, have invented a new, original, and ornamental Design for a Combined Casserole and Tray, of which the following is a specification, reference being had to the accompanying drawing, forming part thereof.

Fig. 1 is a side elevation of the combined casserole and tray showing my new design viewed from one direction;

Fig. 2 is a side elevation viewed from a direction at right angles to the direction of Fig. 1;

Fig. 3 is a plan of the combined casserole and tray, and

Fig. 4 is a view of the side wall of the tray, more in detail.

I claim:

The ornamental design for a combined casserole and tray, substantially as shown and described.

HOWARD H. SCHOTT.
